**SAMPLE HOLDER AND METHOD FOR
SPECTROGRAPHIC ANALYSIS**

Henry Todd, Monongahela, Pa., assignor to United States Steel Corporation, a corporation of New Jersey

Application March 16, 1955, Serial No. 494,686

8 Claims. (Cl. 313—146)

This invention relates to an improved holder for samples undergoing spectrographic analysis and to an improved method of spectrographic analysis.

The holder and method of my invention are used with samples which have a relatively large flat surface, contrasted with pin-shaped samples. Conventionally such holders include a carbon electrode and a means for mounting the sample with its flat surface spaced a standard distance above the electrode. A high voltage electric current is applied to the sample and electrode to produce an arc therebetween. A suitable spectroscope is used for analyzing light from this arc to furnish an analysis of the sample.

An object of the present invention is to provide a holder in which the electrode and sample are relatively movable while the latter undergoes analysis, whereby the arc emanates from various spots on the sample to assure a more representative analysis.

A further object is to provide an improved holder which is adapted to accommodate samples of either standard or non-standard dimensions while moving them relatively to the electrode.

A further object is to provide an improved sample holder in which the sample mounting means carries a spacer for positioning the electrode and is movable manually to align the spacer with the electrode for spacing the latter, and thereafter is motor driven while the sample actually is being analyzed.

A further object is to provide an improved method of spectrographic analysis in which the spot on the sample where the electric arc emanates continually varies to assure a more representative analysis.

In accomplishing these and other objects of the invention, I have provided improved details of structure, a preferred form of which is shown in the accompanying drawings, in which:

Figure 1 is a top plan view of a sample holder constructed in accordance with my invention;

Figure 2 is a vertical longitudinal section on line II—II of Figure 1;

Figure 3 is a horizontal section on line III—III of Figure 2;

Figure 4 is a vertical section on line IV—IV of Figure 1;

Figure 5 is a fragmentary perspective view of the holder illustrating an oversize sample mounted therein; and

Figure 6 is a view similar to Figure 4, but showing a larger oversize sample mounted in the holder.

My holder comprises a base 10, a plurality of posts 12 upstanding from said base, and a platform 13 supported on said posts in spaced relation above the base. The platform is of rigid insulating material, such as a suitable plastic, and preferably is composed of upper and lower sections 13a and 13b to facilitate fabrication. A carriage 14 of conductive material, preferably hard steel, is mounted on the platform 13 for movement in a longitudinal direction, either manually or by a power drive as hereinafter explained.

The base 10 carries an electrode support 15 to which a spring clamp 16 is attached. An upstanding carbon electrode 17 is mounted in the support 15 and held by said clamp. The platform 13 contains an elongated slot 18 which receives said electrode with the upper end of the electrode terminating below the underface of the carriage 14 a standard distance x. The underface of the carriage carries an electrode spacer 19 which rides loosely in the slot 18 as the carriage moves. To space the electrode properly, the carriage is moved manually to a position where the spacer 19 is directly above the electrode 17 and the latter is shoved manually upwardly until it abuts the spacer and clamped. To facilitate thus positioning the carriage, the upper face of the platform 13 preferably has an index marking 20 with which the edge of the carriage is aligned when the spacer is aligned with the electrode.

The carriage drive illustrated includes a screw-threaded shaft 21 journaled in a longitudinal recess 22 in the upper face of the platform 13. The shaft 21 is driven from a reversible electric motor 23, friction wheels 24 and 25, a worm 26, and a worm gear 27 which is keyed to the shaft. A transverse shaft 28 is journaled within the carriage 14 and carries a worm gear 29 located within a recess 30 in the underface of the carriage. This latter worm gear meshes with the threads on the shaft 21. A brake 31 is mounted in a vertical bore in the carriage 14 for engagement with the transverse shaft 28 (Figure 4). A set screw 32 is threadedly engaged with the carriage within this bore and bears against the top of the brake 31. Tightening the set screw applies the brake to the shaft 28, while loosening the set screw releases the brake. When the brake is applied, the worm gear 29 is fixed, whereby rotation of the screw-threaded shaft 21 moves the carriage. The carriage can be moved manually by turning the worm 26, since the friction wheels 24 and 25 allow relative slippage. The upper face of the platform contains guide grooves 33 and the carriage has corresponding tongues which ride therein.

The carriage 14 contains a socket 34 which is longitudinally aligned with the electrode spacer 19 and is adapted to receive a sample S of standard dimensions (for example $\frac{1}{2}$ inch in diameter). The underface of the sample is flush with the bottom of the carriage and located where it can be traversed across the electrode 17. After the electrode is positioned as already described, the carriage 14 is moved back manually to a position where one edge of the sample is directly over the electrode. The motor 23 then is operated in the appropriate direction to traverse the carriage and sample slowly across the electrode, while the circuit to the electrode and sample is energized to produce an arc therebetween. Electric connections to the carriage 14 and electrode 17 are indicated schematically at 35 and 36 in Figure 2. The edge of the platform 13 has a recess 37 through which the arc is exposed to a spectroscope (not shown). The platform contains a horizontal duct 38 for exhausting the fumes created by the arc. Preferably the duct has a connection to a suitable exhaust fan, not shown.

As shown in Figure 5, the end of the carriage 14 carries a sample clamping plate 39 for mounting oversize samples S₁. The plate 39 is fixed to rods 40 which are slidably mounted in bores in the carriage. Preferably the bores also contain tension springs 41 which urge the rods and clamping plate to a retracted position (Figure 1). The end face of the carriage contains a vertical groove 42 which is longitudinally aligned with the electrode spacer 19. The sample S₁ is clamped between the plate 39 and the end face of the carriage within the groove 42. After an oversize sample is thus mounted, it is analyzed in the same fashion as a standard sample S, except that the starting position of the carriage

for traversing the sample is of course farther to the left. If necessary, adjustments in the starting position can be made by releasing the brake 31 from the shaft 28 and manually shoving the carriage 14 with the gear 29 rolling along the threaded shaft 21.

As shown in Figure 6, still larger samples S_2 can be mounted directly on the platform 13 outside the clamp plate 39. The carriage can traverse such samples across the electrode simply by pushing them along the platform. The carriage 14 carries a pivoted contact arm 43 to establish an electric connection to a sample mounted in this fashion.

According to the method of my invention, the holder is set up by manually moving the carriage 14 to align the electrode spacer 19 with the electrode 17 and clamping the electrode with its upper end abutting the spacer. The sample is installed on the carriage as shown either in Figure 2, 5 or 6 depending on its dimensions, and the carriage moved manually to a position where the edge of this sample overlies the electrode 17. Electric current is applied to the electrode and sample to produce an arc therebetween, which arc is exposed to the spectroscope via the recess 37. At the same time the motor 23 is operated to drive the carriage and traverse the sample slowly across the electrode. Since the arc emanates from continually varying spots on the sample, a more representative analysis is assured.

While I have shown and described only a single embodiment of my invention, it is apparent that modifications may arise. Therefore, I do not wish to be limited to the disclosure set forth but only by the scope of the appended claims.

I claim:

1. A holder for samples undergoing spectrographic analysis comprising an electrode, sample mounting means adapted to position a sample in spaced relation to said electrode, means for applying electric current to the electrode and sample to produce an arc therebetween, and means for traversing the sample in a straight line relative to the electrode and thus moving the spot on the sample from which the arc emanates across the sample at a continually changing distance from the edges thereof.

2. A holder for samples undergoing spectrographic analysis comprising a support, a carbon electrode mounted on said support, sample mounting means carried by said support and adapted to position a sample in spaced relation to said electrode, means for applying electric current to the electrode and sample to produce an arc therebetween, and drive means for traversing the sample in a straight line relative to the electrode and thus moving the spot on the sample from which the arc emanates across the sample at a continually changing distance from the edges thereof.

3. A holder for samples undergoing spectrographic analysis comprising a fixed support, a carbon electrode mounted on said support, a movable carriage mounted on said support, sample mounting means on said carriage adapted to position a sample in spaced relation above said electrode, means for applying electric current to the electrode and sample to produce an arc therebetween, and drive means for moving said carriage in a straight line for traversing the sample relative to the electrode and thus moving the spot on the sample from which the arc emanates across the sample at a continually changing distance from the edges thereof.

4. A holder for samples undergoing spectrographic analysis comprising a fixed support, a carbon electrode mounted on said support, a manually movable carriage mounted on said support, an electrode spacer on the bot-

tom of said carriage adapted to be positioned over the electrode for regulating the spacing between the electrode and carriage, sample mounting means on said carriage adapted to position a sample in spaced relation above said electrode, means for applying electric current to the electrode and sample to produce an arc therebetween, and drive means for moving said carriage in a straight line for traversing the sample relative to the electrode and thus moving the spot on the sample from which the arc emanates across the sample at a continually changing distance from the edges thereof.

5. A holder for samples undergoing spectrographic analysis comprising a fixed base, a platform of rigid insulating material supported above said base, a carbon electrode mounted on said base, said platform having an opening for said electrode, a carriage movably mounted on said platform, sample mounting means on said carriage adapted to position a sample in spaced relation above said electrode, means for applying electric current to the electrode and sample to produce an arc therebetween, and drive means for moving said carriage in a straight line for traversing the sample relative to the electrode and thus moving the spot on the sample from which the arc emanates across the sample at a continually changing distance from the edges thereof.

6. A holder as defined in claim 5 including a plurality of sample mounting means on said carriage for accommodating samples of varying dimensions, said carriage being releasable from said drive means to allow it to be moved manually to position the sample with respect to the electrode.

7. A holder for samples undergoing spectrographic analysis comprising a fixed base, a platform of rigid insulating material supported above said base, a carbon electrode mounted on said base and extending upwardly therefrom, said platform having an elongated opening receiving said electrode, a carriage movably mounted on said platform, an electrode spacer on the underface of said carriage and riding in said opening and adapted to be positioned over the electrode for regulating the spacing between the electrode and carriage, sample mounting means on said carriage adapted to position a sample in spaced relation above said electrode, means for applying electric current to the electrode and sample to produce an arc therebetween, and drive means for moving said carriage in a straight line for traversing the sample relative to the electrode and thus moving the spot on the sample from which the arc emanates across the sample at a continually changing distance from the edges thereof, said drive means being releasable from said carriage to allow the latter to be moved manually for positioning the electrode spacer or sample over the electrode.

8. A holder as defined in claim 7 including a plurality of sample mounting means on said carriage for accommodating samples of varying dimensions.
